DESIGN FOR A RADIATOR SHELL

Fred M. Young, Racine, Wis., assignor to Young
Radiator Company, Racine, Wis., a corporation
of Wisconsin

Application October 14, 1940, Serial No. 95,832

Term of patent 14 years

To all whom it may concern:

Be it known that I, Fred M. Young, a citizen
of the United States, residing at Racine, in the
county of Racine and State of Wisconsin, have
invented a new, original, and ornamental Design
for a Radiator Shell, of which the following is
a specification, reference being had to the ac-
companying drawing, forming part thereof.

Fig. 1 is a top plan of a radiator shell embody-
ing my new design;

Figure 2 is a front elevation thereof; and
Figure 3 is a side elevation thereof taken from
the right of Figure 2.

I claim:

The ornamental design for a radiator shell,
substantially as shown.

FRED M. YOUNG.
